UNITED STATES PATENT OFFICE.

GEORGE WILSON AND SAMUEL BERNSTEIN, OF CHICAGO, ILLINOIS.

WATER-HEATER.

SPECIFICATION forming part of Letters Patent No. 544,019, dated August 6, 1895.

Application filed May 8, 1894. Serial No. 510,521. (No model.)

To all whom it may concern:

Be it known that we, GEORGE WILSON and SAMUEL BERNSTEIN, citizens of the United States, residing at Chicago, in the county of 5 Cook and State of Illinois, have invented a new and useful Improvement in Water-Heaters, of which the following is a specification.

Our invention relates to an improvement in the class of heaters which have come to be 10 known in the art as "instantaneous water-heaters" and are designed for heating water while it courses through the apparatus, especially for bath purposes, on merely igniting a suitable burner at the base of the heater and 15 turning into the latter the cold-water supply.

Our present improvement in the features 20 of its general construction partakes of the nature of that set forth in Letters Patent of the United States No. 429,800, granted to Samuel 25 Bernstein, one of the present applicants, on the 3d day of June, 1890.

The objects of our improvement are to provide for preparatorily warming the water admitted to the apparatus in its course therein 25 to the spraying mechanism, which serves to impinge it in a finely-divided condition upon the heat-imparting surfaces in the heater and which direct it to the discharge, to provide for utilizing the steam generated by the operation of the apparatus to commingle with 30 and exert its deodorizing effect on the products of combustion from the burner, and to improve the construction of the apparatus generally and in matters of detail, the better 35 to adapt it for its rapid-heating function.

Referring to the accompanying drawings, Figure 1 represents our improved water-heater by a view in vertical central sectional elevation with the supply and outlet pipe details shown broken. Fig. 2 is a view in elevation of the inner spiral-flange-carrying shell of the jacket enveloping the heater. Fig. 3 is a plan view of the spraying-head. Fig. 4 is a similar view of the distributing-head. Fig. 45 5 is a plan view of the yoke for conducting the water-supply which enters the distributing-head to the spraying-head, and Fig. 6 is a broken view showing the feed-pipe deflector detail.

50 A is the base of the apparatus, preferably

of cylindrical shape, formed of sheet metal, and provided with numerous perforations to admit air to the burner B, supported in the base, and which may be of the construction represented or of any other suitable construction. As illustrated, the burner comprises an annular chamber r, supported in horizontal position in the base A and perforated in its upper side, as at x, the opening in the annulus containing an annular burner-head q, communicating with the chamber r through a threaded coupling r', which supports in its position the head q, the latter being perforated, as at x', in its upper side and covered by a perforated plate p. 55

The burner B, which forms no part of our invention, being old and therefore not illustrated in all its minor details, is adapted for heating by gas as the fuel, and to that end has a pipe o of comparatively-large diameter leading at one end into the annular chamber r, the opposite end being in the form of a funnel o', the more readily to draw in air with the gas, which is supplied by the pipe n, provided with suitable shut-off-valve mechanism. 60

On the upper edge of the base A is seated a water-jacket C, preferably of the illustrated cylindrical shape as to its body portion, with an expanded base portion m, closed about its lower edge, and a contracted upper end m'. 65 The jacket C is formed with two concentric similarly-shaped sheet-metal shells l and l', affording the annular space l' or chamber between them, the course through which, from the point in the base m at which the cold-water supply-pipe k enters the space, is rendered spiral by a spiral flange l², extending about the outer surface of the inner shell l' from near its lower end nearly to the contracted upper end, the spiral flange extending entirely or nearly across the chamber l'. The jacket C envelops a vertical cylindrical or tubular sheet-metal shell C', surmounting the central portion of the burner B and containing an upwardly-tapering sheet-metal shell C², fastened or sealed about its lower flaring edge to the adjacent inner edge of the shell C' and surrounded near its upper end by the annular spraying-head D, which seats 70 on an offset or corrugation i, formed in the 75

shell C'. The spraying-head is corrugated or serrated, as shown at v v' , respectively, about its periphery and central opening to afford numerous small openings. On an annular diaphragm h , in which the upper tapering end of the shell C² is fastened or sealed, are secured the two hollow legs g' (to coincide with openings t in the diaphragm) of a yoke E, the hollow body g of which, and from which the legs proceed, supports a disk-shaped baffle-plate F for the products of combustion passing through the shell C², and is connected by a screw-coupling e with an annular distributing-head F, into the lower side of which the contracted end of the jacket C enters, the head F, which thus crowns the water-jacket, having three internal radial branches e', which open into the coupling e.

From the base of the upwardly-flaring water-chamber G, formed between the shells C' and C², proceeds the outlet-pipe d' to a hollow head d, (shown cone-shaped,) and from the lower end of which extends the draw-off pipe d², provided with a suitable valve; and from the upper end of the head d extends a valve-controlled pipe d³, through the jacket C into the annular space s between the jacket and shell C', for the products of combustion from the burner-openings x.

30 The heater is surmounted by a suitably-ornamented cap H.

The operation is as follows: Upon turning on the gas to the burner and lighting it, so that the products of combustion pass upward through the shell C² and space s, escaping through the cap H, after having imparted their heat to the surrounding surfaces in the heater, water under suitable pressure is admitted from the pipe k into the jacket C, being directed therein by a deflector k' at the inlet to follow in the direction of the arrow in Fig. 2 the spiral course about the chamber l², whereby it is preparatorily warmed on its way to the distributing-head F, from which it is directed through the branches e' and coupling e into the yoke E and by the legs g' of the latter upon the spraying-head D. To leave the spraying-head, the water must pass through the small openings afforded by the serrations v and v', which direct it in finely-divided condition into the chamber G, wherein it contacts with the surfaces of the intensely-heated shells C' and C², and in coursing down the latter becomes hot. In discharging the hot water when boiling through the pipe d², the valve in the pipe d³ should be open to admit the steam, which passes with the water from the chamber G into the head d, to the annular flue or passage s therein to commingle with the products of combustion and exert its deodorizing effect thereon.

We show in Fig. 1 an extension d⁴ of the pipe d², provided with a shut-off valve and intended to lead to a shower, (not shown,) and to be used with the valves in the pipes d² and d³ closed. It may be stated, however, that in

practice the apparatus is not intended to be convertible from a shower to a bath-tub-filling device or vice versa, so that when it is to be used for the first-named purpose the head d and pipes d² and d³ may be omitted, the pipes d⁴ and d' then being continuous or one and the same pipe, as indicated by dotted lines, and where it is to be used for the last-named purpose the pipe d⁴ will be omitted.

75 What we claim as new, and desire to secure by Letters Patent, is—

1. In a water-heater having a burner in its base-portion, the combination with the inter-communicating water-jacket and water-chamber forming the intermediate passage for products of combustion, of a water-supply pipe leading into the jacket, a hollow head into which the water-chamber discharges and having a draw-off pipe, and a steam-pipe connecting the head, from its upper end, with the said intermediate passage, substantially as described.

80 2. In a water-heater the combination of a burner in the base-portion, an annular water-heating chamber about a central passage for products of combustion from the burner, a water-jacket surrounding said chamber and forming therewith an intermediate passage for products of combustion from the burner, 85 a distributing-head into which the jacket empties at its upper end, an annular spraying-head surmounting said chamber and provided with circumferential and internal openings thereto, a water-supply pipe leading into the jacket at the base thereof, and an outlet-pipe leading from said chamber, substantially as described.

90 3. In a water-heater the combination of a burner in the base-portion, an annular water-heating chamber about a central passage for products of combustion from the burner, a water-jacket surrounding said chamber and forming therewith an intermediate passage for products of combustion from the burner, 95 a distributing-head into which the jacket empties at its upper end, an annular spraying-head surmounting said chamber and provided with circumferential and internal openings thereto, a water-supply pipe leading into the jacket at the base thereof, and an outlet-pipe leading from said chamber, substantially as described.

100 4. In a water-heater, the combination with the water-jacket C provided with an inlet and the water-chamber G provided with an outlet and forming with said jacket the passage s, of a burner in the base-portion, a distributing-head F at the upper end of the water-jacket and having a depending yoke E and a circumferentially serrated spraying-head supported over said water-chamber below the yoke and upon which said legs discharge, 105 substantially as described.

110 5. In a water-heater, the combination with the water-jacket C provided with an inlet and

the water-chamber G provided with an outlet and forming with said jacket the passage s, of a burner in the base-portion, a distributing-head F at the upper end of the water-
5 jacket and having a depending yoke E, a covering plate h for the chamber G and through which said legs open at their lower ends, and an annular spraying-head D supported over

10 said water-chamber below the covering plate and provided with circumferential and internal serrations, substantially as described.

GEORGE WILSON.
SAMUEL BERNSTEIN.
